UNITED STATES PATENT OFFICE.

GUSTAV BARTHEL, OF DRESDEN, GERMANY.

LAMP OR BURNER.

SPECIFICATION forming part of Letters Patent No. 506,201, dated October 10, 1893.

Application filed September 28, 1892. Serial No. 447,207. (No model.)

To all whom it may concern:

Be it known that I, GUSTAV BARTHEL, a subject of the King of Saxony, residing at Dresden, Saxony, in the German Empire, 5 have invented certain new and useful Improvements in Lamps or Burners, of which the following is a specification.

My invention relates to vapor burners adapted for burning spirit or hydrocarbons 10 without the employment of a wick the spirit being in practice adapted to be supplied under pressure and caused to burn in a blue flame, and among the objects in view is to provide a burner of the class described by 15 which I avoid the disadvantages resulting from the employment of the oils usually burned in such burners (such as benzine, ligroine or petroleum spirit) in combination with the usual wick, which latter soon becomes clogged with resinous residues.

A further object of my invention is to replace the oils mentioned by spirit which is cheaper and comparatively safe, and with these objects in view, the invention consists 25 in the novel construction, arrangement and combination of parts as hereinafter fully described, illustrated in the drawings and pointed out in the appended claim.

In the drawings:—Figure 1 is a vertical 30 section of my burner adapted for cooking purposes. Fig. 2 is a like view showing a soldering tool or iron applied thereto. Figs. 3 and 4 represent the wire gauze roll or reel in elevation and in section. Fig. 5 is a section of the said roll or reel and burner pipe.

It is well known that the vapors arising 35 from spirit have the property of very rapidly settling down and condensing and it was therefore necessary to devise special means to 40 meet this difficulty. This result is attained in the present invention by making provision for a rapid and uniformly distributed evaporation while a certain counter pressure is allowed to act upon the vapors whereby their 45 settling down is prevented. The means employed for accomplishing this object may vary but practical experience has shown that in order to insure a uniform conduction of heat and evaporation rolls of thin wire-gauze 50 should in preference be employed, while in order to produce the required pressure it is only necessary to raise the spirit reservoir to

the required level, into which reservoir, which may be connected with the burner by any suitable means, air may be forced by any 55 suitable forcing device.

Into a suitable support or base 1, there is screwed a supply pipe 1^a, provided with a handle 1^b and a burner pipe 2. The latter is by an intermediate piece 3, divided into two 60 sections the lower being the evaporation chamber and the upper the vapor combustion chamber. The piece 3 is provided with a narrow opening or mouth 4 having a small tube or nozzle 5 that may be fitted to it or to 65 the pipe 2 as shown and into which nozzle 5 a spindle 6 with a tapering point is inserted from the outside and projecting through an opening in the pipe 2, and adapted to close and open one end of passage 4, and thereby 70 control communication between the lower evaporation chamber and the upper vapor combustion chamber. Suitable packing is employed for making a tight joint between the nozzle and spindle.

The pipe 2 is provided with openings 2^b for admitting air. The lower end of pipe 2 is closed by a perforated bottom 7. Above it is arranged the heat-distributor occupying the whole of the evaporation-chamber, which distributor in the present case is formed of a 75 roll or reel 8 of thin wire-gauze.

In starting the burner, the pipe 2 is first heated in the well-known manner by spirit poured into the cup or basin 9 secured to pipe 85 1^a. Then by means of an adjustable cock (not shown) arranged in the supply pipe, as much spirit is admitted into the evaporation chamber as can be instantaneously evaporated. The spirit being introduced under 90 pressure becomes distributed throughout the whole of the wire-gauze while at the same time the condensation of the vapors is obviated by the fact that the vapors remain in contact with the heated wire up to the very 95 moment when they are allowed to escape through passage 4. By means of spindle 6 the escape or discharge of the gas may be controlled if desired but this can also be accomplished by the cock of the supply pipe *i. e.* by 100 simply not admitting more of it to evaporate than is actually required. This is important in the case where the burner is used for sol-

dering purposes, for in this manner no liquid will be left in the apparatus while it is capable of being turned in any required direction. By raising or lowering the spirit reservoir the 5 pressure may be correspondingly increased or diminished, and the flame regulated.

Instead of the reel of wire gauze separate pieces of wire or thin rods may be employed to fill the evaporation chamber, this arrangement offering the advantage of facilitating the cleaning of the burner.

In Fig. 2 I show a soldering tool 10 removably secured to a standard 11 which is suitably mounted upon pipe 2.

15 What I claim is—

The combination with a base 1, of a supply pipe 1^a secured to said base, a burner pipe 2, also secured to the latter and in communication with the supply pipe, a partition 3 ar-

ranged in the burner pipe, a port 4 in said partition and providing communication between the two chambers of the burner pipe, a nozzle secured to the pipe 2 and provided with a spindle 6 having a tapered point adapted to open and close the port 4, wire-gauze 8 25 arranged in the lower chamber of the burner pipe and extending from the lower end thereof up to a point in close proximity to the partition 3, air-openings 2^a in the latter above the partition 3, a basin 9 secured to the said 30 burner pipe, and a handle secured to the base all arranged as and for the purpose set forth.

In testimony whereof I have hereunto set my hand in presence of two witnesses.

GUSTAV BARTHEL.
